UNITED STATES PATENT OFFICE.

PAUL H. GRIMM, OF GLEN COVE, AND FRANK L. COCKS, OF NEW YORK, N. Y., ASSIGNORS TO ARBUCKLE BROTHERS, OF NEW YORK, N. Y., A FIRM COMPOSED OF WILLIAM A. JAMISON, CATHERINE A. JAMISON, AND CHRISTINA ARBUCKLE.

PACKAGE-FORMING MACHINE.

1,133,858.

Specification of Letters Patent.

Patented Mar. 30, 1915.

Original application filed March 23, 1914, Serial No. 826,637. Divided and this application filed July 13, 1914. Serial No. 850,675.

To all whom it may concern:

Be it known that we, PAUL H. GRIMM and FRANK L. COCKS, both citizens of the United States, residing, respectively, in 5 Glen Cove, in the county of Nassau and State of New York, and borough of Brooklyn, county of Kings, city and State of New York, have invented certain new and useful Improvements in Package-Forming 10 Machines, of which the following is a specification.

This invention relates to package-forming machines and has for an object to provide mechanism for incorporating in a container or package when the same is in process of manufacture, a sheet for adding to the security afforded by the container. This is preferably a sheet impervious to moisture, and may be of some suitably prepared 15 paper, thus tending to preserve from deterioration the material which is afterward placed in the package. The added sheet may be applied in the form of a lining if desired.

20 An object of the invention is to securely hold the sheet of impervious material in position upon the matrix during movements preliminary to the folding or wrapping operations.

25 The present application is a division of our copending application Serial No. 826,637, filed March 23, 1914 for "package-forming machines."

In the drawings accompanying this application a practicable embodiment of the invention is illustrated in which,—

Figure 1 is a side elevation of a portion of a package forming machine certain of the parts being broken away to illustrate 30 the relation of the parts lying beyond. Fig. 2 is a plan view of the wrapping and folding mechanism. Fig. 3 is a vertical section taken on the plane at about the line 3—3 of Fig. 2; and Fig. 4 is a vertical section 45 taken on a plane at about the line 4—4 of Fig. 2.

That portion of a package forming machine or packaging machine which supplies the paper wrappers to the folding or forming devices, is illustrated herein. There is shown at A a stack of wrappers in position to be lifted and transferred to the folding device. This stack is shown upon a suitable

stack support or holder A' which is advanced automatically in some suitable manner, in the present instance a screw A² being provided for this purpose; such feeding however being no part of the present improvement it is not described in detail. 55

The object of a portion of the mechanism 60 illustrated is to feed forward at regular intervals sheets a from the stack A and to apply to or impose upon the uppermost sheet of the stack an interlining sheet b. The sheet b is fed forward over the topmost 65 sheet a of the stack into such a position that the lifting and forwarding device will engage both sheets simultaneously and lift them and transfer them. In the Smyser machine above referred to the uppermost 70 sheet of the stack is engaged by pasting mechanism, the paste being utilized in the transferring, and after the sheet has been transferred to the folding device such paste is utilized for the purpose of holding the 75 wrapper in its folded position. In the present mechanism the added sheet is placed in such a position relatively to the position of the uppermost sheet in the stack and to the working point of the pasting and transferring 80 mechanism, that the imposed sheet shares the paste with the sheet of the stack. The two sheets are moved simultaneously and held together and are so fed or supplied to the folding device. 85

There are shown four pasting and transferring devices C which are caused to revolve step by step in steps of 90 degrees in a horizontal plane, and are also caused to reciprocate vertically, between the steps 90 taken, from the horizontal plane. Each of these pasting devices is shown carried by an arm c, which arms are fast upon a plate c' fast upon a vertical shaft C', which shaft is mounted in suitable bearings in the framework of the machine, and is held in its upward position by yielding means. Each of the plates C is provided upon its under side with paste receiving feet c² for engaging the pasted surface of paste disk c³, which 100 paste disk is caused to rotate and its surface be thereby supplied with paste from a reservoir c⁴. The stack holder A' is disposed at a position below one of the between step positions of the plates C, and the 105 paste disk c³ is disposed at another such po-

sition, so that these two portions of the device are disposed at angles of approximately 90 degrees about the shaft C'. In the mechanism illustrated the point of delivery of the sheets from the pasting and transferring mechanism is the matrix H disposed substantially diametrically opposite the position of the stack holder A'.

The lining paper is illustrated of less width than are the sheets a, and is fed over the stack so that its forward edge comes to rest prior to reaching the forward edge of the uppermost sheet upon the stack, so that there is exposed a margin a' on the upper surface of the uppermost sheet of the stack at three edges of the sheet b. The pasting feet c² are of such area that they engage this exposed margin and the edge of the sheet b adjacent thereto (see wavy lines in Fig. 2). When such feet are covered with paste and are depressed upon the superposed sheets a and b, the paste which otherwise would be applied to the surface of sheet a is shared by it with the sheet b, and upon the rising of the pasting device the two sheets are raised and transferred together.

Feeding rolls are provided for feeding the paper stop between the shear blades b¹⁵ which rolls are driven by a sprocket wheel g and chain g'. The paper is guided over the stack of sheets A into a position to be severed by the shears. The shear blade b¹⁶ is shown provided with an upstanding end b¹⁹ located in the path of movement of shear actuating devices b²⁰ carried by the plate c' upon the descent of the shaft C'.

Each of the pasting and transferring devices stops in turn over the matrix H, the matrix and associated parts here illustrated being substantially those illustrated in the Smyser patent. Upon the downward movement of the transferring devices the interposed sheets a b are placed upon the upper surface of the matrix, whereupon the stripper I descends and holds the sheet or sheets in position during the upward movement of the transferring device. The stripper is illustrated in Fig. 11. After the stripper and the transferring device have been sufficiently advanced in their upward movement, the matrix H is advanced toward the formers J J, that is, it is moved in the direction of the arrow in Fig. 2. In the use of some papers in this mechanism, particularly waxed or impervious papers, difficulty has been experienced in keeping the sheet of paper in position upon the matrix, and also in keeping it in its proper position upon an associated sheet. For instance when the sheet b is an impervious or waxed sheet, and the sheet a is of some other paper having no affinity therefor, there is a tendency for the slippery waxed paper to slip during the subsequent movements of the matrix, which movements consist in the

matrix being shifted from its horizontal position to the dotted line position shown in Figs. 2 and 4. When paper is drawn from a roll and drawn over surfaces in the manner described for the lining sheets, the paper becomes charged with a certain amount of static electricity which causes it to curl or buckle. For preventing the movement of the waxed paper and for the purpose of preventing the movement of one sheet relatively to the other, when more than one sheet is employed, a clamping device is illustrated, designated in a general way by the reference character K. A rock shaft k is shown carried at one edge of the matrix H. Upon this rock shaft are mounted clamping fingers k' k² provided respectively with tails k³ k⁴. Suitable springs k⁵ are provided for holding the clamping fingers normally in their clamping position. In operation, the clamps are opened when the matrix is in position to receive the sheets. The clamps are then closed upon the sheets to hold them in position at the commencement of the movement of the matrix, and are in operative position during the tilting of the matrix. The clamps are also automatically released just prior to the time the sheet will be delivered from the matrix to the former. Lugs k⁶ are provided at the edge of the matrix, which is the forward and downward edge according to the various positions of the matrix. A post k⁷ is shown secured to a suitable portion of the frame of the machine in such position that the tail k³ will be engaged by it and both clamping fingers raised from the matrix upon this assuming its rearmost horizontal position. The front corner of the post is shown rounded at k⁸ for acting as a cam to rock the shaft k, and also to prevent too sudden a movement of the parts responsive to the springs when released from the action of such post. A slight forward movement of the matrix in the direction of the arrow in Fig. 2 releases the clamping fingers, which then engage the sheets. An engaging device k⁹ is provided for the tail k⁴ and is located in such a position upon the framework of the machine that such tail will be engaged and the shaft k rocked in time to release the clamping fingers from the paper as this is drawn around the former.

The operation of the machine is substantially as follows:—The pasting and transferring devices illustrated operate substantially in the manner set forth in the Smyser patent above referred to and their operation will not, in this part of the description, be specifically mentioned except in connection with the explanation of the associated parts, except to state that at time intervals the paste-covered feet c² come into position over the stack A and descend and rise and advance. At each descent the paste-covered

feet will engage the uppermost sheet of the stack, apply paste thereto and utilize such paste in raising and forwarding the uppermost sheet of the stack. After a sheet *a* 5 has been raised the present mechanism will supply beneath it one of the extra lining sheets as a rider for the uppermost sheet of the stack by forwarding the lining sheet to position. The mechanism for forward- 10 ing and severing the rider or lining sheet is timed in such relation to the actuation of the pasting and forwarding mechanism that such rider sheet will be in position for sharing with the uppermost sheet of the stack 15 the engagement of the lifting and forwarding mechanism.

What we claim is:—

1. In package forming mechanism, the 20 combination with wrapping means embodying a matrix and a former associated therewith, of means for transferring sheets of paper to such matrix, means for moving the matrix from its receiving position to the former, clamps for holding the sheets 25 upon the matrix, means for normally closing the clamps, and clamp releasing means located at the receiving and delivering positions of the matrix.

2. In package forming mechanism, the 30 combination with sheet supporting means,

of mechanism for pasting and transferring the sheet from such supporting means, mechanism for imposing a sheet upon said sheet in position to share with the same the paste from the pasting mechanism, a ma- 35 trix for receiving the superimposed sheets, and means upon the matrix for holding the sheets thereon in the relative positions they occupy at the time of their engagement by the pasting and transferring mechanism. 40

3. In package forming mechanism, the combination with a sheet supporting device, means adapted for laying a liner sheet upon each such sheet, a combined paster and transerrer adapted for pasting and 45 transferring said superposed sheets, a matrix and a former for folding the said sheets, and means carried by the matrix for automatically engaging the sheets and holding them in their superposed positions occupied 50 on the transerrer.

In witness whereof, we have hereunto signed our names in the presence of two sub-scribing witnesses.

PAUL H. GRIMM.
FRANK L. COCKS.
